United States Patent

Des. 237,121
Patented Oct. 7, 1975

237,121

TOOL CHEST OR SIMILAR ARTICLE

Mark J. Metzner, Glencoe, Ill., assignor to
Glovemakers, Inc., Chicago, Ill.

Filed June 6, 1974, Ser. No. 477,044

Term of patent 14 years

Int. Cl. D3—02

U.S. Cl. D87—1

FIG. 6

FIG. 7

FIG. 1 is a front perspective view of a tool chest showing my new design; the opposite rear view being similar thereto without the lock;

FIG. 2 is a side elevational view thereof on a reduced scale;

FIG. 3 is a front perspective view thereof in an opened position, with the top tray in a partially raised position;

FIG. 4 is a top plan view of the tool chest in open position with the tray in storage position;

FIG. 5 is a top plan view of the tool chest in open position with the top tray removed;

FIG. 6 is a cross-sectional view taken on the line 6—6 of FIG. 4; and

FIG. 7 is a cross-sectional view taken on the line 7—7 of FIG. 4.

I claim:

The ornamental design for a tool chest or similar article, as shown and described.
